UNITED STATES PATENT OFFICE

WILLIAM H. McSHANE, OF KANSAS CITY, MISSOURI

DESIGN FOR A PEANUT WARMER

Application filed March 21, 1932. Serial No. 43,251. Term of patent 7 years.

To all whom it may concern:

Be it known that I, WILLIAM H. McSHANE, a citizen of the United States of America, residing at Kansas City, in the county of Jackson and State of Missouri, have invented a new, original, and ornamental Design for a Peanut Warmer, of which the following is a specification.

Fig. 1 is an elevation of a peanut warmer showing my new design, the lower part thereof being lined for red.

Fig. 2 is a plan view of the peanut warmer shown in Fig. 1.

I claim:

The ornamental design for a peanut warmer, as shown and described.

In testimony whereof I affix my signature.

WILLIAM H. McSHANE.
